UNITED STATES PATENT OFFICE.

RICHARD G. WOOD, OF CINCINNATI, OHIO.

REGISTERING AND CANCELING BALLOT-BOX.

SPECIFICATION forming part of Letters Patent No. 340,069, dated April 13, 1886.

Application filed December 4, 1885. Serial No. 184,705. (No model.)

To all whom it may concern:

Be it known that I, RICHARD G. WOOD, a citizen of the United States, and a resident of Cincinnati, in the county of Hamilton and State 5 of Ohio, have invented certain new and useful Improvements in Ballot-Boxes, of which the following is a specification.

My invention is an improved ballot-box, the object of which is to insure a fair election 10 and prevent the ballots deposited from being tampered with, others added to them, or the register indicating the number of ballots cast changed after the election is closed, or after the ballots cast are counted. These objects 15 are accomplished by providing means whereby but one ballot at a time can be conveyed into the box and properly marked, and any ballots folded or bunched together, even though previously marked with an exact counterfeit of 20 the stamp upon the printing-roll within the box, will be detected; also, improved means to give audible notice when each ballot is cast and visible notice of the number of honest 25 ballots deposited; also, means whereby the contents of the box, including its mechanism, is inaccessible except when all the judges are present, and inaccessible to any one except the returning-officer after the ballots are counted and returned to the box.

30 The invention will be first fully described in connection with the accompanying drawings, and then particularly referred to and pointed out in the claims.

Referring to the drawings, in which like 35 parts are indicated by similar reference-letters wherever they occur throughout the various views, Figure 1 is a front elevation of the upper part of my box with the cover elevated to a vertical position, exposing in plain view 40 the mechanism which is secured to the inside of the top. Fig. 2 is a vertical section of the closed box, taken through line $\alpha\alpha$ of Fig. 1; Fig. 3, a vertical section taken through line yy , Fig. 1. The feeding and marking devices are 45 removed to expose the devices to automatically lock the opening through which the crank which operates the mechanism, is introduced.

The body of the box A and cover B, when made of wood, are securely framed together, 50 so that it will be impossible to remove or separate the parts without breaking it to pieces.

The whole of the mechanism, with the exception of the locks and stop for the crank-arm, are supported in metal hangers C D, which are secured to the inside of the top. The main 55 or driving shaft E has its bearings in both the hangers C and D. Upon it is secured a roller, F, between the two side flanges, d, of the hanger D. This roller has an undercut or dovetail groove turned in its periphery to receive a 60 rubber band, G, which has upon it the number of the ward and precinct in raised letters. Upon one end of this roller is a cog or gear wheel, f, which meshes into another gear-wheel h, which is secured to an elastic roller, H, 65 both roller and gear-wheel being mounted upon a shaft which has its bearings in the flanges d. The rollers H and F are in close contact, so that when the crank e is turned to revolve the shaft E they will carry the ballot, 70 which is passed through a perforation, b, into the box, the ballot at the same time being printed with the number of the ward and precinct at which the ballot-box is used. The end of the shaft E has preferably a screw-thread 75 upon it to receive the crank e, the end of which is bored out and screw-threaded to engage the screw in the end of the shaft.

I is a roller mounted in a swinging frame, and which is covered with a felt or other absorbent material capable of holding a sufficient quantity of ink to supply the type upon the rubber band G for printing the necessary 80 number of ballots. It is held in contact with the printing strap or band G by a spiral 85 spring, i.

Between the words "Ward" and "Precinct" upon the rubber band G is a projecting pin, h', which extends slightly beyond the letters upon the band G. This pin may be 90 secured in the roller F and extend through the band; or it may be a tack or pointed nail passed through the band from the inner side. Its object is to perforate the ballots as they are carried between the roller F and the elastic 95 roller H, so that should two or more ballots be folded together they would all be punctured by this point h', and thus indicate upon all but one, even if they had been previously marked, the attempted fraud.

The shaft E extends through downwardly-projecting flanges or lugs upon the plate C,

and opposite the plate is provided with a worm, e' , which meshes into a worm-gear, j , which is secured upon a shaft, J . This shaft J has secured upon it a worm, j' , which meshes 5 into a worm-gear, k , which is secured upon a spindle, k' , which spindle is secured to or is a part of the dial K , which is countersunk into the top of the cover B . This dial is made of brass or some other resonant metal, and has 10 its upper edge spaced off, the number of spaces being so arranged that each revolution of the shaft E will advance it the distance of one space.

The indicator-hand k^2 , secured on top of the 15 cover and projecting slightly over the edge of the dial, indicates the number of ballots carried into the box at any given time. The spindle k' of the dial has its bearing in the hub c , which is a part of the plate C .

20 The top of the box is perforated beneath the dial at l , to permit the hammer l' upon the end of an arm, L , to strike the dial and emit a sound at each revolution of the shaft E . This is accomplished in the following manner: 25 The arm L is pivoted upon a bolt, l^2 , which passes through a lug projecting from the plate D . The end of this arm opposite the hammer l' is held in contact with a cam or wiper-wheel, M , secured upon the shaft E by a spiral spring, M , 30 which is compressed between a projecting lug, l^3 , and the plate D .

Now, it will be seen from the foregoing that at each revolution of the shaft E by means of the crank e one ballot will be carried into the 35 box, the dial K advanced one number by the worm-gearing, that an alarm will be sounded upon the dial, which also serves as a gong, and that the ballot will be printed with the number of the ward and precinct by the type-band and punctured, so that only the one 40 printed by the type-band will have the perforation in the proper place.

The crank e is stopped at every revolution when a ballot has been passed through the 45 feeding-rollers by a spring-plunger, N , which projects through the side of the box A in the path of the crank e , being held out in its projected position by a spring, n , which is compressed between the head of the plunger N 50 and the end of the pocket n' , within which the plunger N is pressed to permit the end of crank e to pass and turn the shaft another revolution when another ballot has been passed through the opening b into the bite of 55 the rollers F H .

When the crank e is removed at the close of the election, the opening in the side of the box through which it is passed is automatically locked by the spring-arm O . (Clearly shown 60 in Fig. 3, the dotted line showing it in the closed position and locked by a spring-catch, P , after the crank is removed, and the full line showing it in position to permit the introduction of the crank, which can only be introduced when the box is open by holding the 65 arm O in the position shown in full line, Fig. 3.)

Q Q are two locks, each requiring different

keys to open them. These are placed upon opposite sides of a permutation-lock, R , the dial of which is locked to the dial-plate by a 70 thumb-screw, r , when the lock is retracted, to prevent it from being locked, and the combination "thrown" until the ballots are counted. The bolt of this lock, when thrown, engages a catch, r' , which is secured to the 75 cover.

S is a hinged arm, to prevent the cover from being thrown so far back as to strain the hinges.

The box is intended to be used in the following manner: The dial is rotated until the pointer k^2 is opposite zero. The combination of the lock R is then set, and the dial of the opened lock secured by the set-screw r , the crank-arm e placed in the box, the box closed 85 and secured by the locks Q , and the two keys given one to each of the election judges or supervisors. At the opening of the polls the officers open the box for inspection, the crank e is taken out and screwed upon the end of 90 shaft E , the spring-arm O being pressed down for that purpose. The box is then closed and locked, and the election proceeds until the close of the polls, when the crank e is immediately removed and delivered to some officer 95 who has no key, to be held by him until the ballots have been counted, the return made out, and the ballots returned to the box, when the screw r is removed from the combination-lock and it and the crank placed in the box, 100 after which the box is closed and locked with the keys held by the judges, and the dial of the combination turned to throw the tumblers out, after which the returns and the two small keys of the box are sealed up and delivered 105 to the returning board or officers, who at the time the returns are opened and counted are furnished with the combination of the lock R , in case it should be necessary to verify the return by the ballots in the box.

The means herein described, whereby the contents of the box, including its mechanism, is inaccessible to any one except the returning-officers after the ballots are counted and returned to the box, is not claimed herein, as 115 the subject-matter of the same is intended to be made the subject of a separate application.

What I claim is—

1. In a ballot-box, the combination of the 120 printing-roll F , the type-band G , the puncturing-point h' , the inking-roll I , and pressure-roll H with the shaft E and crank for operating said rolls, substantially as shown and described.

2. A ballot-box mechanism adapted to convey a ballot into the box and print the same in its passage through the feeding-rolls, in combination with the printing-band and a puncturing-point, h' , to puncture the ballots 125 conveyed into the box.

3. In combination with a registering ballot-box, the revolving dial K , located outside of the box and actuated by the feeding mechan-

ism, which conveys the ballots into the box, with a knocker also actuated by the mechanism which feeds the ballots to strike said dial and give audible notice when a ballot is deposited.

4. The combination, substantially as specified, of the shaft E, the cam secured upon said shaft, the dial K, upon the outside of the box and revolved by suitable gearing, such as is shown, driven by the shaft E, lever L, the

spring P, to hold one end of the said lever in contact with the cam M, the knocker L at the opposite end of the arm, and the top of the box provided with the opening L, through which the knocker strikes the dial to sound 15 an alarm when a ballot is deposited.

RICHARD G. WOOD.
